 Budd Induction Heating, Inc., Philadelphia,
 Pa., a corporation of Michigan

Original application May 10, 1941, Serial No.
 392,867. Divided and this application May 25,
 1942, Serial No. 444,347

4 Claims. (Cl. 219—13)

This application is a division of my copending application Serial No. 392,867, filed May 10, 1941, for "Heat treating apparatus."

The present invention relates to heat treating apparatus, more particularly to mechanism for holding and progressively moving the work relative to the heating and quenching mechanism, one of the objects being to provide a new and improved means for holding a hollow cylindrical member to be heat treated and rotating the same while at the same time progressively moving it relative to heating and quenching mechanism from one end to the other to internally harden the same.

Another object is to provide such apparatus wherein the member to be heat treated is accurately held and moved during the heat treating operation.

Another object is to provide such apparatus which is readily accessible for loading and unloading and in which means is provided for insuring proper mounting of the workpiece before operation can be effected.

A further object is to provide such apparatus with improved mechanism for securely gripping a hollow cylindrical workpiece at its opposite ends and which can be readily adjusted to accommodate workpieces of different lengths.

With the above and other objects in view which will be apparent from the following detailed description, the present invention consists in certain features of construction and combinations of parts to be hereinafter described with reference to the accompanying drawings, and then claimed.

In the drawings which illustrate a suitable embodiment of the invention:

Figure 1 is a perspective view of the apparatus looking toward the front and one side of the same;

Figure 2 is an enlarged front view of the work supporting apparatus, portions of the same being shown in section to illustrate some of the detailed construction;

Figure 3 is a horizontal section taken substantially on line 3—3 of Figure 2;

Figure 4 is a horizontal section taken substantially on line 4—4 of Figure 2;

Figure 5 is a schematic layout showing the hydraulic control circuit for the work supporting apparatus;

Figure 6 is a fragmentary side elevation of one of the control devices, and

Figure 7 is a fragmentary section showing the

guide and bridging means for the heating head arbor.

Referring to the accompanying drawings in which like numerals refer to like parts throughout the several views, and particularly to Figure 1, there is generally illustrated a heat treating apparatus comprising a rigid upright frame 40 of hollow box section having a vertical channel or recess 42 in the front face thereof, providing, in effect, spaced vertical columns 44 and 46 at either side of the forward face of the box section frame. On the front face of the frame and secured to the columns 44 and 46 is a pair of spaced upright parallel rods 48 and 50 secured to the frame at the bottom through clamping members 52 and 54 and at the top by clamping members 56 and 58. The rods extend through the top clamping members 56 and 58 and support at their upper extremities a cross tie or bridging member 60, upon which is mounted a switching transformer 62 and its motivating cylinder 64 and from which depends the electrical conductor arbor 66, which elements do not form part of the present invention. Slidably mounted on the rods 48 and 50 is a carriage 68 composed of sleeves 70 and 72 telescoped upon the rods 48 and 50, which sleeves are rigidly connected together at the bottom, centrally and the top, respectively, by the lower chuck support member 74, the upper chuck support member 76 and a guiding bridge 78. Between the upper and lower chuck supports 76 and 74, which carry the upper and lower fixtures 79 and 71, respectively, the workpiece 80 in the form of a tubular cylindrical object is held in proper position for the operations to be performed thereon by the apparatus.

In the lower portion of the apparatus and between the clamping members 52 and 54 there is provided a bracket 82 from which a quenching apparatus 84 is supported, the nozzle of which, as will be later described, projects above the bracket 82 and the actuating elevating and retracting apparatus 86 therefor extends below the bracket 82.

It will be observed that the rods 48 and 50, the rigid frame 40, the bracket 82, and the rigid carriage 68 are sufficient to provide a rigid support for maintaining the conductor arbor 66, workpiece 80 and quench rod 84 accurately in alignment with one another for precision work.

Referring to Figure 2, wherein the central portion of the apparatus is illustrated in detail and in section, it will be observed that the rods 48 and 50, upon which the carriage 68 slides, are

composed each of tubular members 88 and 90, the latter being solid along its upper length and the two being joined together by an intermediate piston member 92 threadedly secured to the tubular members 88 and 90 forming the rods 48 and 50. Each of the sleeves 70 and 72, previously referred to, constitute cylinders adapted to cooperate with the pistons 92, the sleeves 72 being sealed at their ends with suitable glands 94. The sleeves thus form double acting cylinders and through the introduction of fluid under pressure through the ports 98 and 100 above and below the piston rings 93 respectively in the pistons 92, fluid under pressure is admitted to the annular cavity between the members 88 and 90 of the rod 50 and the sleeve 72, it being understood that admission of fluid above the piston will elevate the sleeves 70 and 72 and admission of fluid under pressure below the piston 92 will lower the sleeves 70 and 72.

The carriage 68 is formed by the main lower chuck or lower fixture support member 74 which constitutes a main tie between the sleeves, the same being bored to receive the sleeves and secured to the sleeves 70 and 72 by the split annular keys 102 arranged partly in the annular grooves in the sleeves 70 and 72 and between the lower ends of the sleeve receiving bores 75 of the support member 74 and the retaining collars 104. The member 74, substantially at its center, is provided with a vertical axis bearing constituted by spaced antifriction bearings 110 and 112, upon which is rotatably supported the spindle 114 of the lower work supporting rotatable member 116.

Secured to the underside of the support member 74 is a gear housing and motor support 118, a motor 120 being shown in connection therewith (see Figure 1). The spindle 114 of the lower rotatable work support member 116 is provided at its lower end with a drive gear 122 keyed thereto and meshing with pinion 124 on the shaft of the motor 120 (see Figure 4). The bearing spindle 114 of the lower work support member 116 at its upper end is provided with a radial flange 126 and a depending peripheral cylindrical flange 128, the flange 126 supporting an annular lower splash guard 130 and chuck receiving support plate 132. A drain 133 is provided for the splash guard and plate, the drain being provided with a check valve 135 to prevent back-flow of quenching fluid radially outward therethrough due to centrifugal force of rotation.

The chuck support plate 132 is provided with a central chuck sleeve 134 threaded into the plate 132 and locked by the set screw 138. The chuck sleeve 134 is provided with an outwardly extending radial flange 139 adapted to seat upon the upper surface of a flange on the chuck receiving support plate 132. The upper portion of the chuck sleeve is provided with a plurality of uniformly circumferentially spaced work gripping fingers 142 supported upon paraxially arranged resilient leaf spring members 144, the latter being fastened to the exterior of the chuck sleeve 134 and above the flange 139. Within the chuck 134 is an annular recess in which is positioned an annulus 147 of radially arranged laminations of magnetic material, the laminations acting as an end extension for the workpiece 80 illustrated as supported in the chuck 134.

In order to support tubular articles, such as 80, of considerable length from each end and to provide for the accurate alignment of the workpiece 80, the quench member and the heat head and to facilitate loading and unloading of the apparatus,

the upper chuck support 76, the fixture 79, and the chuck 148 of the same general construction as chuck 134 are provided, in which the chuck 148 and fixture 79 are movable toward and away from the lower chuck 134.

The upper chuck support member 76 will be seen to comprise (see Figure 2) a central bridging member 150 having semi-circular recessed side portions 152 and 154 adapted to engage the sleeves 70 and 72 and to be clamped in tight engagement therewith by the semi-circular caps 156 and 158 secured in place upon the chuck support member by the cap screws 160. In practice, to accommodate workpieces of different lengths, the upper chuck support member 74 may be positioned along the sleeves 72 of the carriage at any desired point by loosening the cap screws 160 and sliding the support member 74 to any desired point.

The bridging member 150 of the upper chuck support member 76 has a substantially annular channel sectioned wall 162 in which are arranged at substantially uniformly spaced points around the periphery three cylinders 164 having pistons 166 from which depend supporting piston rods 168 which carry the upper chuck 148 and its associated fixture 79.

The piston rods 168 are connected through ears 171 to an annular bearing housing member 170. The housing is provided with an inwardly and upwardly extending flange 172, having spaced antifriction bearings 174 which in turn rotatably support a chuck supporting flanged sleeve 173 through the upper end plate 180 and external bearing sleeve 182, the latter coaxing with the antifriction bearings 174 for rotatable support. The sleeve 182 is provided with gear teeth 184 which mesh with a pinion mounted on the motor shaft 186 of the motor 188, the pinion and gear having the same ratio as the pinion 124 and gear 122 and the motor 188 being identically the same as the motor 120. The motor 188 is mounted upon the annular bearing housing member 170 as seen in Figure 2, and the central bridging member has its annular wall 162 offset as at 190 to clear the motor 188 since it will appear that the motor and chuck and annular housing member 170 all are elevated and lowered with respect to the bridge member 150 when fluid under pressure is delivered to the cylinders 164. The annular bearing housing member 170 is provided on its underside with a depending annular upper splash guard 192 extending around the upper chuck 148. It will appear that the upper chuck 148 is threaded into a chuck plate 194, the latter being secured to the lower flange 196 of the flanged sleeve 173. The upper chuck 148 is identical to the lower chuck with the exception that it may be desirable to provide the upper chuck with an opposite thread to that of the lower chuck so that rotation in one direction tends to maintain both chucks tight.

The elevating cylinders 164 are connected together at top and bottom by manifolds 200 and 198, each manifold connecting the lower ends of each of the cylinders and the upper ends together respectively, as is indicated at 202 and 204. The manifolds are each provided with connection 206 secured to the side of the annular wall 162 and from thence to the source of operating fluid pressure as will be hereinafter described.

The apparatus, as illustrated in Figures 1 and 2, shows the heat treat head 212 and the quench head 214 carried at the upper end of the quench apparatus 84 in operative position with respect to the work 80. To commence the heat treat-

ment of the internal surface of the cylinder sleeve workpiece 80, it merely is necessary to energize the heat treat head 212, supply the quench head with quenching fluid and move the carriage 68 and the workpiece 80 downwardly past the heat treat and quenching heads.

Since in order to place the workpiece in the position shown, the heat treat head and the quench head must be separable from one another, provision is made for elevating the quench head 214 into the position shown and retracting the same to a lower position through the agency of a fluid pressure cylinder 216 and piston 218 to which latter the quenching apparatus 84 is connected. The cylinder 216 is supported beneath the bracket 82 through the upper cylinder head 220, the latter having a flange 222 bolted to the underside of the bracket 82. The cylinder 216 is threaded into the upper cylinder head as at 224. The lower end of the cylinder 216 is closed by the lower cylinder head 228 and a port 231 for supplying fluid pressure to the lower end of the cylinder is provided therein.

In order to provide for the supply of quenching fluid to the quenching head 214, the piston 218 is so constructed and arranged as to act as a slide valve to the end that the quench head when in elevated position may be supplied with quenching fluid through a hollow piston rod 230, which forms a part of the quenching apparatus 84 and connects the elevating piston 218 with the quench head 214. The piston 218 is provided with a central annular groove 232 adapted to cooperate with a series of ports 234 in the wall of and at the upper end of the cylinder 216, the ports connecting with an internal annular passage 236 in the depending sleeve or skirt 226 of the cylinder head so as to provide a passage to the annular groove 232 in the piston from a quenching fluid supply pipe 238 connecting with the annular internal groove 236. The annular groove 232 is connected to the bore 244 of the piston through radial ports 248. The upper head 220 is additionally provided with a fluid passage 250 at the end of the cylinder 216 for the admission of fluid to the upper end thereof for acting on the upper side of the piston lowering the quenching apparatus under fluid pressure.

In order to provide for the drainage of quenching fluid supplied within the workpiece 80 from the quench head or nozzle 214, the spindle 114 of the lower rotatable work support is larger in diameter than the piston rod 230 to provide an adequate annular drain passage to a point adjacent the bottom of the lower motor support casing member 118, which is secured to the main chuck support member 74, both being non-rotatable.

The bottom of the gear casing and motor support member 118 is provided with a central aperture 252 and an upstanding sleeve 254 therearound, the upstanding sleeve having at its upper end a fluid-tight washer 256 engaged with the lower end of the rotating spindle 114. A chamber 258 through which the quench tube 230 passes is provided with a water-tight packing 260 at the lower end thereof and is secured to the underside of the bottom of the motor support and gear casing 118 and in alignment with the aperture 252, the chamber being provided with an offset drain pipe 262 so that the quenching fluid passing down through the spindle 114 may be freely carried away therethrough.

The heating head 212 supported from the arbor 66 is supplied with electrical energy from a trans-

former (not shown, but clearly described in my copending application aforesaid) mounted within the housing 62.

Since it is essential for safe operation of the machine that the upper and lower chucks 148 and 134 be precisely in correct engagement with the workpiece 80 and that the workpiece be of proper length, a limit switch is provided to prevent operation of the apparatus in the event that the upper chuck and the lower chuck do not position themselves accurately with respect to each other for a given piece of work. For this purpose, as will appear in Figure 1, the upper chuck carrying fixture 79 is provided with a bracket 270 (see also Figure 6) on the casing 170, to which is secured a rod 272 extending upward parallel with the vertical axis of the machine. The rod is adapted to reciprocate with the opening and closing of the upper chuck fixture 79 through a guide bracket 274 secured to the upper chuck support member 76 and in order to accurately indicate the precise position which the chuck 148 should take when in proper engagement with a particular workpiece 80, the upper end of the rod 272 is provided with an adjustable cam 276 adapted to engage and actuate the plunger 278 of the limit switch 280, the latter being supported in the bracket 274. Since the apparatus set forth is adapted to operate upon and treat workpieces of varying length and since precision is required in maintaining the heat treat head accurately centered with respect to the workpiece, the guide bridge or bracket 78 is provided (see Figure 1) to tie the carriage sleeves 70 and 72 and the arbor 66 in positive relative position with respect to one another, the bridge 78 is secured to the sleeves 70 and 72 through the split sleeve receiving clamps 282 and 284. The bridge is provided with a center downwardly extending guide sleeve 286 closely embracing and accurately positioning the arbor 66 with respect to the sleeves 70 and 72. This guide sleeve 286 functions during downward movement of the carriage and thereby the workpiece 80 carried thereby to slide along and maintain the relatively long arbor 66 in coaxial alignment with the workpiece during heat treating of the same.

Referring to Figure 5 in which the hydraulic control apparatus employed in conjunction with the operation of the carriage 68 in its movement upward and downward and the hydraulic fixture or upward chuck movement is diagrammatically illustrated, a dual supply of oil or other hydraulic fluid under pressure is provided, pumps 300 and 302 driven by the motor 304, both pumps being supplied from the sump 306. The pump 302 is adapted to deliver hydraulic fluid under pressure through the pipe 308 to the control valve 310. A fluid pressure relief 312 is provided in the pipe line 308, which is operative to relieve the pressure when the control valve is in the central position as illustrated. Raising the fixture 79 or upper chuck assembly and chuck 148 is effected by energizing valve solenoid 314 to shift the valve 310, so as to deliver hydraulic fluid to the pipe line 316 and through a check valve 318 to the pipe 198, and thence to the cylinders 164 (Figure 2). Lowering of the chuck is prevented by the check valve 318, which is spring biased and prevents the return flow of hydraulic fluid except under positive pressure. Thus to lower the fixture or chuck the valve solenoid 320 is energized to supply hydraulic fluid to the pipe line 200, which forces the pistons in cylinders 164 downward, forcing the discharge of hydraulic fluid through the pipe

line 198 and overcoming the bias of the check valve 318, thereby permitting drainage of the fluid into the sump by passing through the pipe 316 to the valve 314, and thence to the drain pipe 322.

Movement of the carriage up or down is effected through the application of hydraulic fluid under pressure derived from the pump 300 through line 331, which pump is adjusted to deliver hydraulic fluid at a specific pressure so that accurate control may be obtained. Raising the carriage 68 is accomplished by energizing the valve solenoid 324 associated with the valve 326, and valve solenoid 328 associated with valve 330, so that fluid may pass from the pump through the valve 326 to the conduit 332, through the valve 330 to the conduit 334, and thence through a biased check valve 336 to the pipe 100, which admits hydraulic fluid in the annular space in the sleeves 10, 72 above the pistons 92. Hydraulic fluid from the underside of the carriage pistons 92 is discharged from the pipe 98 and through valve 326 to the drain pipe 338 and thence to the sump 306. Lowering the carriage may be effected in two ways, one of which is accurately controlled as to rate of movement, and which is employed during the actual heat treatment, whereas, the other is faster and permits the rapid return of the carriage to the starting position.

The controlled rate is effected by the energization of the valve solenoid 340 associated with the valve 326 so as to deliver fluid under specific pressure from the pump 300 through the pipe 98 to the annular space beneath the pistons 92 in the sleeves 10, 72 thereby tending to force the lowering of the carriage 68 and the workpiece 80. Movement of the carriage downward, however, is restricted by the restricted discharge of hydraulic fluid from the annular space above the piston 92, the discharge being restricted by the metering valve 342, the latter being so adjusted as to fix the rate at which hydraulic fluid may escape to the sump, and thereby positively controlling the return and downward movement of the carriage, so long as the valve solenoid 328 of the valve 330 is deenergized and the metering valve positively connected in circuit with the discharge line 344. For rapid movement downward the solenoid 328 may be energized for shifting the valve 330 to permit discharge through the pipe 332 and thus through the drain 338 after passing through the valve 326, it being understood that the valve 326 is energized by the solenoid 340.

The check valve 336 is biased sufficiently to prevent the return flow of hydraulic fluid therethrough and thus maintain the carriage in any position but yet to permit flow and its movement under the forceful application of hydraulic pressure below the pistons 92, in which case the hydraulic fluid above the piston is forcefully discharged through the check valve and the metering valve to the sump or direct to the sump through line 346, as may be desired.

As described in my copending application aforesaid, the operation of the machine is controlled by a sequence controller (not shown) which may be of any suitable type capable of effecting the necessary operations in sequence. The sequence controller, among other things, controls the energization of the valve solenoids 314, 320, 324, 328 and 340 of Figure 5 and the limit switch 280 is so connected in the circuit that the solenoids 324, 328 and 340 cannot be energized until the limit switch 280 is closed. The limit switch 280 is responsive to the movement of the upper chuck fixture 79 and the actuating

cam 276 can only actuate slide rod 278 to close limit switch 280 when the chuck fixture 79 is in its lowermost position. The lowermost position is the position in which the chuck 148 is in proper engagement with the workpiece 80 to be heat treated. In other words, the workpiece 80 must be properly held by the chucks 142 and 148 before the limit switch 280 can close with the result that the carriage 68 cannot be actuated until the workpiece is in proper coaxial relationship with the inducing head 212 and quenching head 214. Thus, insurance is had that the two heads will be safeguarded against injury through contact with an improperly held workpiece.

15 In the operation of the apparatus, starting from an unloaded condition, the quenching head 214 is separated from the induction heating head 212 and withdrawn into the fixture 71. Also, the carriage 68 is in its lowermost position and the upper fixture 79 is in its uppermost position. During the loading period which is predetermined by the sequence controller, the workpiece to be heat treated is inserted in the lower chuck 144 after which the sequence controller causes energization of the valve solenoid 320, whereby pump 302 causes actuating fluid to flow through line 200 to the upper ends of the cylinders 164 to cause pistons 166 to lower the upper chuck fixture 79, whereby the upper chuck 148 engages and grips the upper end of the workpiece.

20 When the upper chuck 148 is in proper engagement with the workpiece it is in its lowermost position which causes cam 276 to actuate the slide rod 278 to close the limit switch 280, whereby operation of the apparatus can continue. If the workpiece is not properly located in the lower chuck and prevents the upper chuck 148 from reaching its lowermost position, the limit switch 280 remains open and operation can 25 not continue until the position of the workpiece is corrected.

30 Following the closure of limit switch, valve solenoids 324 and 328 energize and pump 300 supplies actuating fluid through valves 326 and 330 and check valve 336 to the sleeves 10 and 72, whereby the carriage 68 is moved to its uppermost position, illustrated in Figure 2, the quench head 214 previously or at substantially the same time having moved upwardly into engagement with the induction heating head. It will be noted that at this uppermost position the lower end of the workpiece 80 is adjacent the heating head 212 for the start of the heat treating operation. Valve solenoids 324 and 328 energize when the carriage 68 reaches its uppermost position.

35 Electrical energy is then supplied to the heating head 212 and quenching fluid is supplied through the pipe 230 to the quenching head 214. Also, the two motors 120 and 188 are started to 40 rotate the workpiece 80. Immediately thereafter solenoid valve 340 is energized to direct actuating fluid to the sleeves 10 and 72 through line 98 resulting in the gradual and uniform speed of the carriage and workpiece in a downward direction 45 relative to the heating and quenching heads, during which movement the inner surface of the workpiece is heated and quenched. The uniform downward travel of the carriage is controlled by the adjustment of the metering valve 342.

50 As the carriage reaches the end position for heat treatment the electric energy is shut off and the supply of quenching fluid is terminated. Also, at this point valve solenoid 328 is reenergized, solenoid 340 being energized, to cause carriage 55 to continue its downward movement at a

rapid rate until its lowermost position is reached, at which time valve solenoids 328 and 340 are deenergized causing the carriage to come to rest. The quench head is then lowered and this is followed by energization of valve solenoid 314 which causes the upper fixture to move upwardly to disengage the chuck 148 from the workpiece. The heat treated workpiece is then removed from the lower chuck.

The carriage and chucking device arrangement described is an improvement on the construction shown in my copending application, Serial No. 349,400, filed August 2, 1940.

Inasmuch as changes in the detailed construction and arrangement of parts may be made without departing from the spirit of the invention, reference will be had to the appended claims for a definition of the limits of the invention.

What is claimed is:

1. In a heat treating apparatus, a work holding carriage comprising spaced parallel members, spaced transverse chuck-supporting members carried by said parallel members, a first chuck carried by one of said transverse members, a chuck supporting element, a second chuck carried by said supporting element in axial alignment with and axially spaced from said first chuck, and means between the other of said transverse members and said chuck supporting element, said means supporting said supporting element and said second chuck for movement axially relative to said first chuck to and from a proper relative chucking position; and means actuated upon improper relative positioning of said chucks for preventing operation of the apparatus.

2. In a heat treating apparatus, a frame, a work holding carriage movable on said frame, means for moving said carriage from a loading position to a work heat treating position, said carriage including spaced work supporting chucks, means for moving one of said chucks toward the other to cooperatively support a workpiece, means responsive to movement of the one chuck relative to the other for indicating a normal loading condition, and means responsive to the indication of a normal loading condition for actuating said first mentioned moving means and moving said carriage to a work heat treating position.

3. In a machine for heat treating a surface of a workpiece, a supporting base, a movable carriage, means on said carriage for securely supporting the workpiece to be heat treated, cooperative guide means on said carriage and base supporting and guiding said carriage for movement through a predetermined linear path, means for effecting said movement, a relatively long stationary head supporting arbor spaced at one end and from said end throughout at least the major portion of its length from said base, a heating head fixed to said end of said arbor, said arbor and head being parallel to said linear path of movement and said carriage being arranged to move the workpiece as supported thereby into and out of closely spaced heating relation with said head, and a guide element rigidly fixed to said carriage for movement therewith and surrounding said arbor in longitudinally slidable bearing engagement for accurately positioning said head with respect to the workpiece during movement of the workpiece by said carriage into heating relation with said head.

4. In a machine for progressively heat treating a cylindrical surface of an elongated workpiece, a base, a relatively long stationary arbor supported at one end of said base and spaced for the remainder of the length thereof from said base, a heating head fixed to the other end of said arbor, a carriage guidably supported on said base for movement longitudinally of and parallel to said arbor, means on said carriage for supporting the workpiece to be heat treated in axial alignment with said head, said carriage having a normal workpiece loading and unloading position and an initial heating position and being movable longitudinally of said arbor from said loading position to move the workpiece as supported thereby throughout its length axially past said head to said initial heating position and return the workpiece to said normal position, means for effecting said carriage movements, and guide means rigidly fixed to and movable with said carriage and surrounding said arbor in longitudinally slidable bearing engagement for maintaining the arbor and the heat head against lateral deflection during return movement of the workpiece past said head.

HOWARD E. SOMES.
